UNITED STATES PATENT OFFICE.

ELBERT S. P'POOL, OF HATTIESBURG, MISSISSIPPI.

STOVE.

Application filed October 3, 1921. Serial No. 504,856.

To all whom it may concern:

Be it known that I, ELBERT S. P'POOL, a citizen of the United States, residing at Hattiesburg, in the county of Forrest and State of Mississippi, have invented new and useful Improvements in Stoves, of which the following is a specification.

The present invention has reference to knock-down or collapsible bodies in which the parts constituting the same may be set up in an easy manner to produce a strong and efficient structure, and wherein said parts may be easily separated and readily handled to arrange one on the other to produce a small compact package for shipment or for storage.

The improvement is particularly directed to heating apparatus, such as stoves or built-out heaters for open grates or fire places, and in carrying out the invention it is my purpose to produce such devices in which the parts thereof can be associated in an easier and more expeditious manner without the employment of bolts, rivets or analogous securing means.

It is also my purpose to produce a knock-down structure in which every element constituting the same is provided upon its confronting and abutting surfaces with integral means designed for interengagement in a manner which will hold all of the parts together in a strong and efficient manner without in any ways detracting from the appearance of the structure.

It is a still further object to produce a heating apparatus in which a collapsible or knock-down body rests and is secured on a collapsible or knock-down base, one in which the draft damper is of a particular construction and associated with the stove in a novel manner, one in which the fire door is normally locked by means on the front or side of the stove which cooperates with the door, one in which the hinged connection between the fire door and the stove is such as to sustain the said door in horizontal position when opened, one in which the ash door comprises a removable element and has associated therewith the damper for controlling the air currents beneath the

grate, one in which the grate comprises removable sections which are arranged in the body of the stove in a novel manner which will permit of the removal thereof when desired, and also one which shall embody various novel features of construction and arrangement of parts such as will herein-after be more fully set forth.

The drawings, which accompany and form part of this application, illustrate a satisfactory embodiment of the improvement reduced to practice, but the nature of the invention is such as to render the same susceptible to various changes and modifications such as will fall within the scope of what is claimed, and therefore the drawings and description are to be considered in connection with only one embodiment of the improvement.

In the drawings:—

Figure 1 is a front elevation of a heating device constructed in accordance with this invention.

Figure 2 is a sectional view on the line 2—2 of Figure 1.

Figure 3 is a sectional view on the line 3—3 of Figure 1.

Figure 4 is a sectional view on the line 4—4 of Figure 2.

Figure 5 is a fragmentary detail perspective view showing base members in position to be assembled.

Figure 6 is a sectional view through the front of the heating device with the fire door in open position.

Figure 7 is a fragmentary detail perspective view of the fire door mounted in its supporting frame.

Figure 8 is a fragmentary sectional view of the front showing the supporting means for the fire door frame.

Figure 9 is an elevation of the heating device applied to an open grate or fireplace.

Figure 10 is a sectional view on the line 10—10 of Figure 9.

Figure 11 is a sectional view on the line 11—11 of Figure 10.

Figure 12 is a fragmentary detail perspective view showing the means of assembling the sides and bottom plate.

Figure 13 is a fragmentary detail perspective view showing the base assembly, and

Figure 14 is a sectional view on the line $x-x$ of Figure 2.

5 It is, of course, to be understood that the improvement is to be constructed in various sizes, shapes, etc., and that any desired material, suited for the purpose, may be employed.

10 In the construction illustrated in Figures 1 to 8, in particular, the base of the heater comprises four sections, which are in the nature of plates. The front plate, indicated by the numeral 1 has its ends flanged in the same 15 direction, as indicated by the numeral 2, and the inner face of the said plate, from the bottom thereof, and in a line with the flanges, but spaced therefrom, is integrally formed with lugs 4, the upper ends of the lugs being 20 reduced or cut away upon their inner faces to provide tongues 4'. The side plates 5 are provided at their upper front corners with lugs 6 which are cut away at the bottom to form tongues 7. Similar lugs 8 having 25 tongues 9 are provided on the side plates at their upper rear corners. The outer edges of the lugs just mentioned are flush with the outer edges of the corners of the side plates. The back plate 12 is similar in construction 30 to the front plate being provided with inwardly directed flanges 13 at each end, and having lugs 11 formed with tongues 10 near each end at the bottom of the plate.

To assemble the base the lower part of the 35 side plates 5 are placed inside of the flanges 2 and 13 on the front and rear plates respectively, and the plates 5 are then slid downwardly in the space between the flanges and the lugs of the front and rear plates. 40 The tongues 7 on the lugs 6 will interengage with the tongues 5 on the lugs 4, and the tongues 9 on lugs 8 will interengage with the tongues 10 on the lugs 11. It is thus 45 apparent that the parts will be held together, and maintained in position, and that the only movement allowed by such arrangement is the upward movement of the side plates. The side plates 5, at the center thereof have their upper edges notched, as 50 at 14. The bottom plate of the stove proper is of a materially greater length and width than the supporting base therefor, the under face of the bottom plate 15 is straight or 55 smooth throughout, and simply rests on the upper edge of the base, the rear edge of the plate 15 being disposed in a line with the back of the base. The bottom plate 15, upon its upper face is provided with slot 60 16 that is designed to align with the notches 14 in the sides 5 of the base, and inward of the slot there are integrally formed on the plate 15 ribs 17, the said ribs having their ends engaging the ends of the transverse 65 rib 18 as shown in Figure 3 of the drawings and said ribs 18 are formed adjacent to the

rear edge of the bottom plate 15. The ribs 17 terminate approximately in a line with the front of the base, being disposed to the rear of said front a distance approximately equalling the thickness of the front 70 plate of the said base, and approximately in a line with the outer edges of the said ribs 17 the plate 15 has other ribs 19, the said ribs 19 being of a materially greater thickness than the ribs 17, while on the outer edge 75 of the plate between the ribs 19 there is a transverse rib 20 preferably of a thickness substantially equalling that of the ribs 17 and 18.

The back plate of the stove is indicated by the numeral 21 and has its lower edge resting on the bottom plate and in contacting engagement with the transverse rib 18. The back plate is provided with spaced lugs 23 that have their lower ends notched from the inner face of the plate to provide 85 tongues 24. The lugs 23 are spaced from the flanges 22 a distance equalling the thickness of the side plate 25 of the stove body.

The back plate 21, on its upper edge is 90 formed with an inwardly directed flange 26.

The side plates 25 have their lower edges approximately centrally formed with extending hook-like tongues or members 27, the same being preferably integrally formed 95 on the outer faces of the side plates and are designed to be passed through the slots 16 in the bottom plate 15 and to enter the notches 14 on the sides 5 of the supporting base. Thus, it is necessary to cant the side plates when arranging the same on the bottom or base plate 15, and when the said side plates are brought to vertical position the inner and lower edges thereof will be 100 in contacting engagement with the longitudinal ribs 17 on the said bottom plate 15. Before proceeding further it should have been stated that the side plates should be positioned upon the base before the back 105 plate is applied thereto, the said side plates having their rear ends provided with inwardly directed lugs 28 that have their upper ends, on their inner faces reduced to 110 form tongues 29, and these tongues are designed to be engaged by the tongues 24 on the lugs 23 of the back plate when the same is moved in a downward vertical direction toward the base or bottom plate 15. In this manner, the back and side plates are 115 effectively secured on the base. The front ends of the side plates, when arranged on the base are in a line with the front ends of the longitudinal ribs 17 of the base or bottom plate 15. The side plates 25 have their 120 front ends, on their inner faces provided with lugs 30 disposed approximately opposite the lugs 23, the said lugs 30 having their inner and upper faces reduced or cut-away to provide the same with tongues 31. The side plates 25, upon their upper edges 125 130

are approximately centrally formed with inwardly directed flanges 32.

The front of the stove comprises a number of sections, the upper and outermost section being in the nature of a frame, and this section is indicated by the numeral 33. The member 33 is open at its center from its bottom to a point adjacent to its upper edge approximately equalling the width of 10 the sides 34 of the said frame or member 33. The sides, upon their inner faces are formed with vertically disposed flanges, and inward of the flanges with parallel spaced lugs 35 which are reduced from 15 their inner faces at their lower ends to provide tongues 36, and these tongues 36 are designed to coengage with the tongues 31 of the side plates 25, when the outer edges of the said side plates are received between the lugs 35 and the flanges 34. It 20 will thus be seen that the frame member 33 is moved downwardly over the outer edges of the side plates, and when the tongues 31 and 36 are in interengagement, as just 25 described, and the back is secured to the sides, the main body of the stove is set up in an easy but strong and efficient manner. When the front member or frame 33 is positioned, the outer face thereof is in contact 30 engaging with the inner ends of the outer and widened ribs 19 on the base or bottom plate 15 which more effectively sustains the body in its set up condition. It will, of course, be obvious that it is not 35 necessary to elevate the back or the front frame 33 above the top edges of the sides in arranging the back and front on the sides, it being merely necessary to arrange the lugs on the said front and back between the lugs on the sides and then move 40 the said front and back downwardly into engagement with the tongues on the lugs of the sides and to permit of the lower edges of the front and back resting on the base. 45 It is to be also understood that the interior of the stove is suitably reinforced to prevent the buckling thereof from heat, and preferably the members constituting the body each comprise two thicknesses between which there is a body of non-heat 50 conducting material, such as sheets of asbestos, but if desired, the inner faces of the body members may be formed of single thicknesses and asbestos facings be secured 55 thereon.

Preferably the front frame 33 is of a greater thickness than the sides or back of the body, the outer portion of the said frame being cut or channeled in a line with its inner edges to provide the same with a continuous depression whose inner wall is indicated by the numeral 37, and the sides of the inner wall provided by the said depression are, at a suitable distance from the top wall 60 thereof formed with lugs 38, the said lugs

being of a width equalling that of the said walls 37 and being of a thickness approximately equalling that of the depression. The lugs 38 have their upper faces cut at a downward and inward angle, providing the 70 same with what I will term hooks and which are indicated by the numeral 39, and the lower walls of the said lugs, from their outer faces are also inclined inwardly, as at 40. The vertical end walls provided by the depression are in a line with the inner walls of the flanges 19, and the opening provided by the member 33 is closed, at the upper portion thereof, by a substantially rectangular frame 41, which also, of course, constitutes an element of the front. The outer face of the frame 41, upon the vertical ends thereof are provided with outwardly extending flanges 42, a similar flange 43 being provided upon the upper edge thereof, while a 80 flange or enlargement 44 is arranged upon the lower edge on the outer face of the frame between the side flanges 42. The side flanges 42 on their outer edges are provided with notches, the upper and lower walls of which being arranged at the same inclinations, the upper inclined portions forming what I will term hooks. The hooks are indicated by the numeral 45, and the notches by the numeral 46. The frame is of a size to be snugly received in the opening of the member 33, and to contact with the walls 37 that surround the opening. The notches 36 are designed to be arranged over the lugs 38 in the vertical walls 37, and the hooks 45 of the frame 100 41 are designed to coengage with the hooks 39 on the lugs 38 of the member 33. The lower inclined walls of the lugs on which the hooks 45 are formed, and which are indicated by the numeral 47, rest upon the inclined surfaces 41 of the lugs 38, and in this manner the frame 41 is effectively secured upon the front member 33.

The lower flange on the frame 41 has its lower edge disposed a slight but suitable distance below the lower edge of the frame proper which is also true with respect to the lower ends of the side flanges on the said frame, and designed to rest against the said edges and ends of the flanges is the upper edge of the inner inclined portion 48 of the combined air draft and ash door 49. The lower portion of the combined draft and ash door is flat and is received on the base or bottom plate 15 and has its outer edge in contacting engagement with the flange 20 and its ends in contacting engagement with the flanges 19. The inclined portion 48 has side flanges 50 which are also in contact with the side flanges 19 when the lower edges of the sides or flanges 50 rest on the bottom plate 15.

The inclined base 49 of the combined ash door and air regulator or draft is provided centrally with a T-shaped slot, the longer 130

branch 51 of which being arranged longitudinally and the shorter and central branch 52 being arranged vertically on the door, and the said inclined portion 48, to the sides of the slot has spaced openings 53 therethrough. The chamber comprises a plate 54 provided with spaced openings 55 and with a central substantially hooked or angle handle 56. The outer and widened portion of the handle 56 is of a size to be passed through the T-shaped slot at the central portion thereof, which is provided with the branch 52. The plate and hook-shaped handle is then permitted to gravitate so that the reduced portion of the handle rests upon the lower wall provided by the longitudinal branch of the T-shaped slot, the widened or angle end of the handle being in contacting engagement with the outer surface of the inclined portion 48 of the ash door. By moving the handle longitudinally through the slot, the openings in the damper plate may be brought to register with the openings in the portion 48 of the ash door and the draft entering the stove through the ash door may be regulated by adjusting the damper plate, as will be readily understood.

The fire door is indicated by the numeral 57 and is in the nature of a substantially rectangular plate of a size to close the central opening in the frame 41. The fire door 57 has its sides and upper edge provided with outwardly extending flanges 58 and 59 respectively, the flanges 58 being notched from their outer edges, as at 60, and the opposed walls provided by the notches being inclined in the same direction, as at 61 and 62 respectively. The upper inclined wall provides what I will term a tongue, and the frame 41 in a line with the vertical walls provided by the central opening therein is formed with lugs 63 whose upper and lower ends are cut at the same inclination, the upper ends providing what I will term hooks 64. The lugs 63 are designed to be passed through the notches 60, and the door 57 is then permitted to gravitate slightly in a downward direction on the frame to bring the hooks 61 thereof into coengagement with the hooks 64 provided upon the lugs 63. The fire door is held in the frame by providing the said door, upon its inner corners with depending fingers 65 that have their lower ends flanged outwardly, as at 66. The door is canted 55 when the flanged fingers are received in the frame, and when the door is in open position, the same will be sustained horizontally by the outer face of the door resting upon the lower flange of the frame and by the offset 60 ends 66 of the fingers 65 being in contacting engagement with the inner face of the frame.

The front member 33 of the stove is provided, upon its inner face with upwardly projected hooks 67, the said hooks designed 65 to be received in slots 68 adjacent to the

ends of the front grate member 69. The sides 5, opposite the front grate member have their inner faces formed with longitudinal flanges 70, and on these flanges rest the main or basket grate 71.

The top plate of the stove is indicated by the numeral 72, and is of a considerably greater width and length than the body of the stove. The top plate is provided with the usual flanged openings for the reception of the disk-like lids, and is also provided with a smoke pipe outlet 73. The stove pipe 73 may be integrally formed with the top, if desired, and when so formed is arranged at an angle so that other pipe sections may be attached thereto in a convenient manner and properly directed to the flue opening in the chimney. The outlet is provided, on one of its sides with an opening, and on its other side with a notch. Through the opening is designed to be passed one end of the stem 74 for the damper valve 76, while the other end of the stem, which has the handle thereon is received in the notch. In this manner, the damper can be easily and quickly applied to the pipe section. The top plate 72, upon its inner face and adjacent to its rear end is formed with a laterally extending flange 77, and the said flange, upon its outer face and at determined intervals is formed with outwardly projecting tongues 78. The under face of the top is likewise formed, adjacent to its ends, with longitudinal lugs 79 that have one of their ends reduced to provide tongues 80. The top is arranged on the body so that the lugs thereof are disposed between the flanges 32 and the front of the body. The top plate is then moved over the body so that the tongues 80 will engage beneath the flanges 32 and the tongues 78 beneath the flange 26. The flange 77, on the top plate, when the lugs are so engaged, will be in contacting engagement with the inner edge of the flange 26, and the sides of the lugs 78 will be in contacting engagement with the inner faces of the side plates 5. In the manner, as above set forth, it will be seen that the various elements constituting a stove, constructed in accordance with this invention, coengage in a manner which will hold the body, when set up, in a strong and efficient manner, while at the same time such means may be readily brought out of co-engagement when it is desired to separate the elements or parts of the improvement. When so disassociated each of the several parts of the stove may be easily handled and all of the parts may be arranged one over the other to produce a small compact package for storage or shipment.

In the construction illustrated in Figure 9, and the remaining figures of the drawings, the improvement is of a means to close an open grate or fire place 81. The rear or back of the improvement comprises a

substantially rectangular frame 82 of a size to fully cover the grate opening. The frame, upon the lower and closed portion thereof has on its outer face, adjacent to its 5 ends spaced vertical flanges 83 respectively, an upper horizontal flange 84 and a lower horizontal flange 85, the last mentioned flange being disposed between the inner vertical flanges. The face 86, instead of constituting four members or plates, as previously described, comprises only three, the outer plate being secured to the side plates in a manner similar to that already described, and the side plates having on their 10 inner and upper ends lugs provided with depending tongues 87 that are designed to engage with similar tongues 88 formed on the inner vertical flanges, the outer vertical flanges being in contacting engagement with 15 the outer faces of the side members of the base. The bottom or base plate has its under face provided with longitudinal or transverse lugs or flanges 89 to receive therebetween the upper edges of the base 20 plate, the inner end of the base or bottom 90 resting upon the referred to horizontal flange on the frame 82. The frame 84 is provided with vertically disposed outer and inner spaced flanges 91 and 92 respectively 25 and at its upper end above the said flanges 91 and 92 with an outwardly projecting flange or enlargement 93. The base 90 is also provided with an inner pair of longitudinal ribs 94 and 95 respectively. The 30 inner ribs 94 and 95 are, in this instance, formed with outwardly extending flanges 96 provided with spaced notches 97. The side plates 98 of the body, at their lower edges are provided with inwardly extending ribs 99 provided with spaced notches 100, and the notches are designed to receive therethrough the tongues provided by the notches 97 in the flanges 96 of the ribs 95, 40 and thereafter to be moved toward the rear frame to bring the notches out of alignment, and the outer faces of the side plates into contacting engagement with the outer ribs 94, and the inner edges of the said plates between the vertical inner and outer 45 flanges 92 on the back frame 82. The front is of a similar construction to that previously described, so that a detailed description thereof is not considered necessary, and also the top 101 is substantially 50 similar to the top plate 72 and coengages with the front and sides in a manner similar to that previously described, the inner edge of the top, in the present instance, underlying the outwardly projecting flange or 55 enlargement on the top of the frame 82. In a like manner, the removable front and basket portion of the grate are supported. The flue damper, in the present instance, 60 regulates the passage between the grate, frame and flue against which the device is positioned, and one of the side plates is provided with an opening 101, the second side plate with a notch 102 disposed directly opposite the opening, the notch being closed by the top plate 103. Through the opening 70 passes one end of the stem 104 for the damper 105. Through the notch there is passed the opposite end of the stem, and the said last mentioned end is provided with a handle portion 106. The damper is 75 in the nature of a flat plate, of a sufficient width to accomplish its purpose, and when the back plate is to be wholly opened to the flue, the handle is moved outwardly to bring one end of the damper against the side 80 plate provided with the notch, the damper then being swung to a substantially horizontal position and moved longitudinally in an opposite direction to permit the end thereof resting on a lug 107 provided upon 85 the inner face of the opposite side plate of the body. Varying forms and designs of interengaging means between the plates or elements constituting the improvement are illustrated in detail in Figures 12 to 15, but 90 as the same coengage in a manner similar to that previously described, and as the manner of such coengagement will be perfectly apparent to those skilled in the art to which this invention relates, a detailed 95 description thereof is not considered necessary.

The stove pipe sections, including the elbows, employed in connection with the stove proper each has one of its ends flanged inwardly and notched, as at 108, and the confronting end of the cooperating section is formed with projecting angle lugs 109 designed to be received in the notches 108, 100 and the sections are given a twist on each 105 other so that the shoulders provided by the lugs will contact with the inner faces of the notched flanges.

It is thought that the foregoing description, when taken in connection with the drawings will amply set forth the construction and advantages of the improvement without further detailed description.

Having described the invention, I 110 claim:

A knock down stove of the character described comprising a plurality of vertical plates interlocked in a manner to provide a rectangular shaped base, a horizontal bottom plate supported by the base and being 115 provided with slots arranged adjacent its side edges, said bottom plate having its front and side edges extending beyond the front and side plates forming the base, a 120 flange rising from the outer edge of the front extension of the bottom plate, flanges formed on the bottom plate and having their ends engaging in a manner to provide a rectangular frame, side, front and rear 125 walls rising from the bottom plate and en-

gaging the frame thereon, means secured to the respective walls for interlocking them in operative position, hook like thumbs depending from the side walls and adapted to be received in the slots of the bottom plate, a fuel door for the front wall of the stove and a combined ash door and air draft plate having angle bent portions formed

thereon for engaging the flange on the front extension of the bottom plate and a portion of the front wall respectively and a top supported upon and secured to the walls as and for the purpose specified. ¹⁰

In testimony whereof I affix my signature.

ELBERT S. P'POOL.
